UNITED STATES PATENT OFFICE.

JOHANN HARDT, OF HINDENBURG, GERMANY, ASSIGNOR TO JOHANNES SOBAWA, OF BRIEG, GERMANY.

COMPASSES FOR DRAWING OVIIFORM CURVES.

Application filed August 5, 1921. Serial No. 490,127.

To all whom it may concern:

Be it known that I, JOHANN HARDT, a citizen of the German Republic, residing at Hindenburg, Germany, have invented certain new and useful Improvements in Compasses for Drawing Oviform Curves, of which the following is a specification.

This invention relates to a compass for drawing oviform curves. The essential 10 characteristic feature of the invention consists in the fact that the compass has three points adapted to be adjusted with regard to one another, a string attached to one of the points being placed around the other 15 points. When a pencil is moved along the inner side of said string so that the string is stretched outward the oviform curve is produced.

In order that the invention may be clearly 20 understood, I shall proceed to describe the same with reference to the form of construction shown by way of example in the accompanying drawing, wherein:—

Fig. 1 is a perspective view showing the 25 compass in use.

Fig. 2 illustrates how the oviform curve is formed.

The shank 1 of a two-shanked compass has in its point 2 an eye through which 30 the ends 3 and 4 of a string are passed. The ends 3 and 4 of the string are then attached to a sleeve 5 which is adjustably mounted on the shank 1 of the compass. A screw 6 serves for fixing the sleeve 5 in its adjusted position. The string forms 35 a loop at the point 2 of the shank the diameter of said loop being varied by the adjustment of the sleeve 5.

A sleeve 8 is adjustably mounted on the 40 second shank 7 of the compass to be fixed in position by a screw 9. The sleeve 8 has two eyes 10 in which the arms 11, 11 are pivoted which are hingedly connected with the lower end 13 of shank 7 by means of 45 articulated pieces 12, 12. The arms 11, 11 terminate in the points 15, 15 and have projections 14, 14 designed to guide the string.

The compass is mounted upon the surface 50 on which the curve has to be drawn so that its point 2 is situated on the middle line of the curve, the points 15, 15 of the compass standing at equal distances from said middle line. The distance between the points 15, 15 is regulated by the adjustment of sleeve 55 8 upon the shank 7.

The points 15, 15 are inside the loop formed by the string. By adjusting the slide 5 upon the shank 1 the size of the loop can be regulated at will. If the string is stretched outward with the aid of a pencil 60 and if the pencil is conducted along the inner side of the string an oviform curve is drawn which is composed of three elliptic curves.

When the point 2 of the compass is 65 mounted at point *a* (Fig. 2), the points 15, 15 being mounted in the points *b*, *c* (Fig. 2), the length of the string which is in contact with the points at *a*, *b*, *c* is not altered between the points *a*, *c* and *b*, *c* so that the 70 pencil describes half an ellipse with the middle line *d*, *d* between two points 20 and 21. When the pencil 16 is moved further the string is fixed between the points *a*, *b* and *a*, *c* and the pencil describes an elliptic 75 curve 21, 23 with regard to the middle line *f*, *f*. The string is finally fixed at the points *a*, *b* and *b*, *c* and the pencil describes the half ellipse 23, 22 to the ellipse middle line *e*, *e*. 80

Any desired shape of an oviform curve can be obtained by varying correspondingly the position of the points 15, 15 the one with regard to the other, that of point 2 with regard to the points 15, 15 and that of sleeve 85 5 upon the shank 1.

I claim:—

1. A compass for the drawing of oviform curves comprising in combination a single point and two points arranged in pair, and 90 adjustably connected to each other, a string adjustably attached with its ends to the single point and placed in a loop around the points arranged in pair so that when said string is being stretched by means of a pencil moved along the inner side of said string the two points arranged in pair act successively as contact points for the string. 95

2. A compass for the drawing of oviform curves comprising in combination a shank 100 having a point provided with an eye, a sleeve adjustably mounted upon said shank, means for fixing said sleeve in adjusted position, two eyes of said sleeve, a second shank without point, a sleeve adjustably 105 mounted on said pointless shank, means for securing said sleeve in adjusted position thereon, two pointed arms hinged to said sleeve, articulated pieces connecting said arms with the end of said pointless shank, 110

projections on the front side of said arms in proximity with the pointed ends of said arms, and a string attached with its ends to the eyes of the sleeve of the pointed shank 5 after they have been passed through the eye of the point so that the string forms a loop, the string being in contact with the outer surfaces of said pointed arms so that when said string is being stretched by means of

a pencil moved along the inner side of the 10 string an oviform curve is drawn by said pencil.

In testimony whereof I affix my signature in presence of two witnesses.

JOHANN HARDT.
